UNITED STATES PATENT OFFICE.

JEAN ROMEYN, OF ST. GILLES, NEAR BRUSSELS, BELGIUM.

INTERNAL-COMBUSTION ENGINE.

Application filed September 13, 1922. Serial No. 588,062.

To all whom it may concern:

Be it known that I, JEAN ROMEYN, a subject of the Queen of Netherlands, residing at St. Gilles, near Brussels, Belgium, have invented certain new and useful Improvements in and Relating to Internal-Combustion Engines, of which the following is a specification.

This invention relates to two stroke internal combustion engines of the type in which the exhaust and scavenging are effected through ports located round the cylinder and these ports are uncovered and closed again by the piston or pistons at the proper time.

The invention refers to certain improvements whereby the "volumetric efficiency" of the cylinder, i. e., the ratio between the volume of fresh air at atmospheric pressure enclosed in the cylinder and the displacement of the piston or pistons, is increased in a practical way.

According to this invention, the part of the exhaust pipe just close to the cylinder is shaped as an auxiliary cylinder in which an auxiliary piston moves. During the exhaust period and the mere scavenging period, the auxiliary piston lies in an enlargement of the pipe, so that the burnt gas and the little excess of scavenging air which is necessary for securing a thorough cleaning can pass freely from the main cylinder to the atmosphere through the auxiliary cylinder. After the scavenging period, i. e. a little past the dead centre, the auxiliary piston enters the auxiliary cylinder in a direction reverse to the flow of exhaust gas, stops the said flow and compresses the burnt gas contained in the auxiliary cylinder and the passage connecting it to the main one, so that the whole quantity of fresh air entering the cylinder is used for the purpose of raising the pressure therein.

In order that this invention may be better understood, it is fully described hereunder with reference to the accompanying drawings, which show by way of example and diagrammatically, two constructions according to its principle.

Figure 1 thereof is a section through the cylinder of an engine of the ordinary type, and Fig. 2 is a section through the cylinder of an opposed piston engine.

Referring to both figures, in which similar parts are indicated by the same letters, a

is the main cylinder; in Fig. 1, the single piston is designated *b*, whereas in Fig. 2 there are two pistons *b* and *c*. Near the end of the power stroke, the piston *b* uncovers the escape ports *d*, and a little later, the scavenging ports are uncovered by the same piston *b* in the case of Fig. 1, and by the piston *c* in the case of Fig. 2. The auxiliary cylinder *f* is connected at one end with the main cylinder through the exhaust channel *g*, and the ports *d*, while at its other end it is connected to the exhaust pipe *h*, which presents an enlargement *j*. The auxiliary piston *k* moves up and down, partly in the auxiliary cylinder and partly in the enlargement *j*; it is actuated by any suitable means; the actuating motion shown on the drawing consists of a rotating crankshaft *l* moving the piston rod *n* by means of the connecting rod *m*.

At the moment the piston *b* uncovers the ports *d*, the piston *k* is situated in the enlargement *j*, so that the exhaust gas can pass out without any perceptible throttling from the main cylinder to the atmosphere through the auxiliary cylinder. The passage to the atmosphere remains quite free until the piston or pistons reaches or reaches a point which is at or beyond the dead centre, so that, when the ports *e*, are uncovered the scavenging process can effectively take place. At the point above referred to, the auxiliary piston *k* enters the auxiliary cylinder and, at once, stops the flow of exhaust gas from *g* to *h* and drives back the gas contained in the space *g*. During the same time, the main piston or pistons has or have started the return stroke, so that the space in the main chamber decreases also. Furthermore, the fresh air flow through the ports *e* goes on for a certain time. For these three reasons, the pressure in the space *g* and in the main cylinder rises. It is possible to proportion the area and speed of the auxiliary piston in such a manner, that during the increase of pressure just referred to there will be only a negligible flow of exhaust gas through the ports *d*. Then the whole of the flow of fresh air through the ports *e* into the cylinder can be said to be used exclusively for raising the pressure in the cylinder. The best conditions are obtained when there is no flow of exhaust gas at all through the ports *d*.

But as that is not practically possible, a little flow from the cylinder into the space *g*

will be allowed for, in order to ensure that no part of the burnt gases, enclosed in the space *g* will pass back into the cylinder.

If this invention is applied to a reversible engine, the shaft *l* has to be turned through a certain angle by the reversing gear, in order that the moment at which the auxiliary piston commences to compress the gas, remains the same for running in the reverse direction.

10 A little change in the setting of the crank shaft *l*, as compared with the main crank shaft, may also be used to increase momentarily the compression for starting purposes; 15 if the auxiliary piston *h* enters the cylinder *f* a little sooner there will be a gas flow from *g* into the cylinder and the compression pressure will be higher. The said flow of gas, although it exerts a bad effect upon the purity 20 of the air charge, may be permitted momentarily for easier starting.

I claim as my invention:—

1. An internal combustion engine, comprising a main cylinder having exhaust and 25 scavenging air ports; piston means for controlling said ports; an exhaust passage into which the exhaust ports open having a portion thereof forming an auxiliary cylinder, said passage being provided with an enlargement 30 immediately adjacent the end of such cylinder remote from the main cylinder; a piston valve and a driving connection operated by the engine and leading to the piston valve for continually and positively reciprocating the latter; said piston valve acting 35 to shut off the air by being moved by said driving connection out of said enlargement into said auxiliary cylinder after the escape of the exhaust gases has taken place, and then being forced, in the opposite direction 40 to the flow of the gases, into the auxiliary cylinder so as to drive the scavenging air which it contains backward toward the main cylinder until the exhaust ports are closed 45 by said piston means.

2. An internal combustion engine, comprising a main cylinder having exhaust and scavenging air ports; piston means for controlling said ports; an exhaust channel into 50 which the exhaust ports directly open; an exhaust pipe leading from said channel and

having a portion thereof forming an auxiliary cylinder, said pipe being provided with an enlargement immediately adjacent the end of such cylinder remote from the main cylinder; a piston valve and a driving connection operated by the engine and leading to the piston valve for continually and positively reciprocating the latter; said piston valve acting to shut off the air by being moved by said driving connection out of said enlargement into said auxiliary cylinder after the escape of the exhaust gases has taken place, and then being forced, in the opposite direction to the flow of the gases, 60 into the auxiliary cylinder so as to drive the scavenging air which it contains backward toward the main cylinder until the exhaust ports are closed by said piston means.

3. A two-stroke internal combustion engine, comprising a main cylinder having spaced exhaust and scavenging air ports; a pair of opposed pistons in said cylinder, one piston for controlling the exhaust ports, and the other for controlling the scavenging air 70 ports; an exhaust passage into which the exhaust ports open having a portion thereof forming an auxiliary cylinder, said passage also having an enlargement immediately adjacent the end of such cylinder remote from the main cylinder; a piston valve movable between a position within the auxiliary cylinder and one within the enlargement of the exhaust passage; and a driving connection operated by the engine and leading to the 75 piston valve for continually and positively reciprocating the latter; said driving connection being so timed as to position said valve within the enlargement when the exhaust commences, and then force it out of 80 said enlargement into the auxiliary cylinder, after the escape of the exhaust gases and a portion of the scavenging air, in the opposite direction to the flow of the gases, to shut off the further escape of the air and 85 to drive it backward toward the main cylinder.

In testimony whereof I affix my signature.
JEAN ROMEYN.
